W. CRAMER

SAW GUARD

Filed Dec. 4, 1920

INVENTOR:
William Cramer
BY
Hugh S. Wagner,
ATTORNEY

UNITED STATES PATENT OFFICE.

WILLIAM CRAMER, OF ST. LOUIS, MISSOURI, ASSIGNOR TO TRUCK, TRACTOR, AND MANUFACTURING COMPANY, OF ST. LOUIS, MISSOURI, A CORPORATION OF MISSOURI.

SAW GUARD.

Application filed December 4, 1920. Serial No. 428,369.

To all whom it may concern:

Be it known that I, WILLIAM CRAMER, a citizen of the United States, residing at the city of St. Louis, in the State of Missouri, have invented certain new and useful Improvements in Saw Guards, of which the following is a specification.

This invention is a sawguard. The objects sought are to provide a device of this kind that is adapted for use with any thickness of material to be cut and that is reliable and effective and that is simple in construction and inexpensive.

In the accompanying drawings forming part of this specification, in which like numbers of reference denote like parts wherever they occur,

Figure 1 is a top plan view;

Figure 2 is a side elevation; and

Figure 3 is a vertical sectional view.

The table 1 supports the saw 2 in any suitable manner.

The guard 3 is composed of the plurality of members 4 and 5, which are tied together by rod 6. Washers 7 and keepers 8 complete the tying.

The band 9 is a safety guard for the guard 3, and prevents accidents by abrasion due to the presence or rotation of guard 3.

The guard 3 being bifurcated, spans or straddles saw 2, and is held in place by the pair of straps 10 and 11. These straps are pivoted at 12 to rod 13, which is attached by bolts 14 to arm 15 supported by standard 16.

Arm 15 is supported through its collar 19 by rod 17, which is journaled in a bearing 18 carried by a standard 16.

A brace 20 extends diagonally from rod 17, which it encircles at 21, to a connection through eyelet 22 fixed in the upper side of the bar or rod 13 at a point between the ends of a pair of straps 10 and 11 which are secured at the opposite sides of the forward end of the bar or rod 13, substantially as shown. The brace 20, as clearly shown in Figure 2, is removably secured at one end to the rod 17 and in abutting relation with respect to the inner end of the bearing 18 thereof by means of a clamp collar 21' and, therefore when its other end is passed through the eyelet 22, accommodates side play of the guard 3 the rod 20 having a sufficient rigidity for the purpose.

Vertical play of guard 3 is permitted by the pivoted connection 23 of bar 24 with the

straps 10 and 11, spring 25 normally holding bar 24 down and with it the members 4 and 5 of guard 3 so as to envelop the dangerous part of saw 2, as shown in Figure 2.

Saw 2 is rotated by shaft 26. Table 1 is supported by the main frame 27, upheld by standards 28.

The members 4 and 5 being pivoted at 6 to the straps 10 and 11 or the like, are themselves adapted to rotate continuously or otherwise under such impulsion as may be received either directly or indirectly from the rotation of the saw 2.

The spring 25 allows bar 24 to rise and fall according to necessity, and with it the straps 10 and 11, and thereby the guard 3 is accommodated and accommodates itself to any thickness of the material 29 that may be passed underneath guard 3 to be sawed by saw 2. Bar 24 is preferably made of spring 75 steel, and is preferably located directly in alinement with saw 2 and acts as a kerf spreader.

Spring 25 and the spring-like quality of bar 24 allow automatic adjustment of guard 3, which is thus always held in engagement with the material 29 to be cut. This adjustment for relatively thick or thin material is quite important and a great convenience, as it saves much time that would otherwise be lost in adjusting a guide more or less like guard 3 from one thickness of material 29 to another. In this machine, the thickness of the material determines the degree of elevation of guard 3 above table 90 1, and the guard 3 is ready at all times for immediate use regardless of the thickness of material 29, and assists in guiding such material as well as guarding saw 2 and preventing fragments from flying away from 95 saw 2.

The rod 13 is pivoted at 30 to the rod 17, and this allows the guard 3 to rise or fall as may be required by the thickness of the material 29. The brace 20 prevents 100 wobbling of rod 13, and is itself pivoted at 21 to rod 17. Thereby a slight but sufficient flexible up-and-down connection is established for guard 3 with rod 17 and the slideable arrangement of rod 20 through eyelet 105 22 produces a slight flexible lateral arrangement of guard 3.

The sawdust is caught in chute 31 and carried away by pipe 32 in the usual manner.

A sawguard that is automatically flexible or adjustable sidewise as well as vertically is a desideratum.

Having thus described this invention, I hereby reserve the benefit of all changes in form, arrangement, order, or use of parts, as it is evident that many minor changes may be made therein without departing from the spirit of this invention or the scope of the following claims.

I claim:

1. In a machine of the class described, the combination with a saw table and a circular saw operably mounted thereon, of a supporting rod secured on said table in rear of and at right angles with respect to the saw and extending for a distance to one side of the same, a rod pivoted at one end to said supporting rod and in line with the saw, a guard carried at the free end of said rod and overlying the saw, an eye carried by said rod at a point inwardly from said saw guard, a brace rod pivoted at one end to said supporting rod and having its other end engaged through said eye, said brace rod extending diagonally between its points of connection with said supporting rod and said eye.
2. In a machine of the class described, the combination with a saw table and a circular saw operably mounted thereon, of a supporting rod secured on said table in rear of and at right angles with respect to said saw and extending for a distance to one side of the same, a rod pivoted at

one end to said supporting rod and in line with the saw, a saw guard carried at the free end of said rod and overlying the saw, an eye carried at the upper side of said rod at a point inwardly of said saw guard, a brace rod pivoted at one end to said supporting rod and having its other end engaged through said eye, said brace rod extending diagonally between its points of connection with said supporting rod and said eye, and a clamping collar cooperative with the pivoted end of said brace rod for securing the same against lateral movement during the operation of the machine.

3. A saw guard, comprising a support, a rod mounted in and projecting from the support, a bar mounted for rotative movement upon the rod remote from the support, means connecting said rod adjacent the support and said bar remote from said support to provide for lateral stability of the bar, a U-shaped frame pivotally connected at the forward end of the bar, spaced guard members rotatably mounted in said frame, a guard band overlying and spaced from said members and having one terminal connected to the U-shaped frame and the other terminal secured to the bar, and spring supported means depending from the bar to permit vertical play of the guard as a whole under tension.

In testimony whereof I hereunto affix my signature.

WILLIAM CRAMER.
